UNITED STATES PATENT OFFICE.

WILLIAM J. SCHWAB, OF CHICAGO, ILLINOIS.

RAIL-FASTENING.

1,076,790.

Specification of Letters Patent. Patented Oct. 28, 1913.

Application filed September 9, 1912. Serial No. 719,342.

To all whom it may concern:

Be it known that I, WILLIAM J. SCHWAB, a citizen of the United States, and a resident of the city of Chicago, county of Cook, and State of Illinois, have invented certain new and useful Improvements in Rail-Fastenings, of which the following is a specification.

My invention relates to improvements in rail fastenings and has for its object the production of a fastening through the medium of which a rail may be secured to a tie without employing spikes or the like, such as are used at the present time for this purpose.

A further object is the production of a fastening which will constantly exert a force upon the rail to hold the same in proper position upon the tie and which will serve to prevent loosening of the rail through usage such as results at the present time by reason of the securing spikes becoming loosened.

A further object is the production of a fastening which will be of simple and economical construction and efficient in use.

Other objects will appear hereinafter.

My invention consists in the combinations and arrangements of parts hereinafter fully described and claimed.

The invention will be best understood by reference to the accompanying drawings forming a part of this specification, and in which—

Figure 1 is a transverse section of a pair of rails mounted upon a tie, said rails being fastened to said tie through the medium of a fastening embodying my invention, one end of said fastening being shown in section, Fig. 2 is an end elevation of the tie, a fragment of one rail being shown thereon, Fig. 3 is a view similar to Fig. 2 illustrating the arrangement employed at the juncture of two abutting rail ends, Fig. 4 is a fragmentary sectional view of the construction shown in Fig. 3, and Fig. 5 is a perspective view of the fish plate employed in conjunction with the fastening.

Referring now to the drawings wherein is illustrated the preferred form of my fastening, a conventional railway tie is shown at 1 upon which is mounted a pair of rails 2. The fastening for securing said rails to said tie comprises an elongated bar 3 which is arranged under said rails, extending between the same and along one of the longi-

tudinal edges of the tie, said bar 3 being of a length such that the ends thereof will project slightly beyond the outer edges of the rail bases. Engaging over the rail bases are plates 4, the innermost of said plates being secured to bar 3 in clamping relation with said rail bases through the medium of bolts 5 and nuts 6. Plates 4 arranged at the outer sides of said rails are secured to bar 3 in clamping relation with said rail bases through the medium of bolts 7 and nuts 8. Said bolts 5 and 7 are so arranged that the same engage against the opposite edges of the bases of the rails so as to prevent lateral movement of the latter.

The lower ends of bolts 7 are connected with the upper ends of helical tension springs 9, the latter being threaded upon the lower ends of said bolts, as clearly shown in Fig. 3. The lower hooked ends of said springs engage the perforated adjacent ends of angular hooked members 10 which engage around the tie, as clearly shown in the several views, the upper ends 11 of the members 10 being turned inwardly to engage over the tie in order to hold said members 10 in secure engagement with the tie. The arrangement is such that the springs 9 will exert a constant pull or pressure upon the bars 3 in order to securely hold the rails 2 upon the tie. If it is desired to increase the tension of said springs it is only required to thread the same farther up upon the bolts 7. Thus, it will be seen, that the rails will be securely fastened to the ties and without the employment of spikes or other analogous securing devices.

At the juncture of two adjacent ends of abutting rail sections, securing devices of the construction set forth will be employed at either side of the tie at which the joint is located, as clearly shown in Fig. 3. In this case, however, securing plates 4' of angular form will be employed, the upwardly extending portions 12 of said plates being adapted to engage against the fish plates 13 employed at opposite sides of the rail at the joint. In order to prevent longitudinal movement of said fish plates, the members 4' are provided with inwardly extending tongues 14 which engage recesses 15 provided in the outer sides of said fish plates at the extremities thereof, as clearly shown in Figs. 4 and 5.

While I have illustrated and described the preferred form of construction for car-

rying my invention into effect, this is capable of variation and modification without departing from the spirit of the invention. I, therefore, do not wish to be limited to the exact details as set forth, but desire to avail myself of such variations and modifications as come within the scope of the appended claims.

Having described my invention, what I claim as new and desire to secure by Letters Patent is:

1. The combination with a tie and a rail mounted upon said tie, of means for fastening said rail to said tie, said means comprising a plate adapted to engage over the base of said rail; a hook member adapted to engage around said tie; and a tension spring connecting said plate and said hook member, substantially as described.
2. The combination with a tie and a pair of rails mounted upon said tie, of means for fastening said rails to said tie, said means comprising a bar arranged under and extending between said rails; means engaging the bases of said rails for fastening the same to said bar; and means for resiliently fastening said bar to said tie, substantially as described.
3. The combination with a tie and a pair of rails mounted upon said tie, of means for fastening said rails to said tie, said means comprising a bar arranged under and extending between said rails; means engaging the bases of said rails for fastening the same to said bar; means for resiliently fastening said bar to said tie, said last mentioned means comprising hook members engaging around said tie; and tension springs connecting the ends of said bars and said hook members, substantially as described.
4. The combination with a tie and a pair of rails mounted upon said tie, of means for fastening said rails to said tie, said means

comprising a bar arranged under and extending between said rails; plates engaging the bases of said rails; bolts passing through said plates and said bars for holding said plates in clamping relation with said rail bases, said bolts engaging against the edges of said rail bases; and resilient means co-operating with said bolts for yieldingly fastening said bars to said tie, substantially as described.

5. The combination with a tie and a pair of rails mounted upon said tie, of means for fastening said rails to said tie, said means comprising a bar arranged under and extending between said rails, angular plates engaging the bases of said rails; fish plates arranged against the webs of said rails, said angular plates engaging against the outer sides of said fish plates and entering recesses provided in said sides of said fish plates; means for securing said angular plates to said bars; and tension springs connecting said bars with said tie, substantially as described.

6. The combination with a tie and a pair of rails mounted upon said tie, of means for fastening said rails to said tie, said means comprising a pair of bars arranged under and extending between said rails and along the longitudinal edges of said tie; angular plates engaging the bases of said rails; fish plates engaging against the outer sides of said fish plates; means for securing said angular plates to said bars; and resilient means for fastening the ends of said bar to said tie, substantially as described.

In testimony whereof I have signed my name to this specification in the presence of two subscribing witnesses.

WILLIAM J. SCHWAB.
